TOWER CONSTRUCTION

Harold Cohen, Elizabeth, N. J.

Application July 28, 1944, Serial No. 547,064

7 Claims. (Cl. 287—58)

1

This invention relates to a device which is useful for rigidly securing to each other parts to constitute a tower, pole or mast suitable for radio antennae or aerials.

An object of the invention is the provision of a device of the indicated character which not only is adapted to secure structural components to each other rigidly, but also to afford good electrical conduction when the parts are made of suitable metal.

A further object is the provision of a suitable number of similar devices of the indicated character, whereby structural components may be rigidly secured to each other to constitute a tower, pole or mast, and which devices enable the use of guy lines for a mast, and which devices also enable the parts of the tower or mast to be detached from each other when it is desired to dismantle the tower or mast.

The nature of the invention and its distinguishing features and advantages will appear when the following specification is read in conjunction with the following drawing, in which—

Fig. 1 is a vertical sectional view through portions of two structural components telescoped and rigidly secured to each other by the use of a device of the present invention.

Fig. 2 is a transverse sectional view taken on the line 2—2 of Fig. 1.

Fig. 3 is a side view of assembled parts shown in Fig. 1.

Fig. 4 is a collective view of the parts of the securing device, said parts being shown in perspective.

In the drawing, there are shown by way of example components, sections or rod members 10 and 11 of a mast or pole which may be used to support an antenna or aerial. Said components 10 and 11 are tubular so that they may be telescoped to provide overlapping portions shown in Figs. 1 and 2.

One or more securing devices is applied to the overlapping portions of the tubular sections to rigidly secure them to each other in extended relation. Only one such device is shown in the present instance. The device is one which may be quickly and easily applied and likewise detached. In the case of a tower, pole or mast to be used to support an antenna for a radio receiving hookup or an aerial for a radio transmitting hookup, the sections or components constituting the structure as well as the parts of the securing devices will be made of metal for electrical conduction purposes.

The securing device consists of three coopera-

2

tive main parts 12, 13 and 14, respectively. The part 12 consists of a cross-bar 15 and a clamping member or abutment 16 rigidly secured, as by welding 17, or by any other means, to the cross-bar 15 on one end thereof and at a right angle with respect thereto. Pins 18 are rigidly secured, as by welding 19, to the clamping member 16 on the opposite ends, respectively. Each of the pins has a point 20. The cross-bar has a longitudinal slot 21 therein near the end opposite that having the clamping member 16. Beyond the slot 21 the cross-bar has a pointed end 22 to facilitate insertion. The cross-bar is of a length which is greater than the diameter of the outer component 10, so that the slotted portion projects beyond the same.

The part 13 is in the form of a bar and constitutes a clamping member or abutment. Pins 23, like the pins 18, are welded, as at 24, to the part 13 on the opposite ends thereof.

The part 14 is wedge shaped and constitutes a pressure exerting and locking key which is receivable in the slot 21 in coaxing relation to the cross-bar 15 and the clamping member 13.

The components 10 and 11 are prepared to accommodate the parts of the securing device, and for this purpose, the component 10 which surrounds the component 11 has holes 25, there being a pair for the pins 18 and a pair for the pins 23 diametrically opposite those for the pins 18. Also, the component 10 has holes 26 diametrically opposite each other which register with holes 27 in the component 11. The holes 26 and 27 are of a size to receive the cross-bar 15, while the pins 18 are in their related holes 25. The pointed ends of the pins 18 and 23 project beyond the clamping surfaces of the respective members 16 and 13 and serve as spacing means to compensate for any inequalities in the relative sizes of the components 10 and 11. Also, these pointed pins are capable of penetrating any coating of paint on the components 11 to bite the latter so as to assure good electrical connection.

To apply the securing device, the cross-bar 15 of the part 12 is extended in the holes 26 and 27, respectively, and the pins 18 are entered into the related holes 25 with the clamping member 16 contacting the component 10. The clamping member 13 is arranged in the slot 21 to extend at a right angle to the cross-bar 15 with the pins 23 in the related holes 25. The key 14 is then placed in the slot between the clamping member 13 and the adjacent end wall of the slot. The key 14 is forced down tightly causing it to bear on the member 13 and at the same time draw the member

3

16 toward the member 13. The pins 18 and 23 will bite the component 11. The member 13 contacts the component 10, and by virtue of the pins 23 sets up a clamping action on the component 11 in conjunction with the pins 18, while the member 16 clampingly engages the component 10. Thus, these components, sections or rod members 10 and 11 are rigidly secured to each other in extended relation for the intended purposes.

It is understood that the required number of components and securing devices will be used to constitute a tower or mast of the desired height. The tower or mast will be rugged and by reason of the construction of the parts a structure of the type mentioned may be quickly and easily erected and dismantled.

The members 14 and 16 may have provision, such as the holes 28, to accommodate guy lines to aid in sustaining a mast or pole erect.

I claim:

1. A structure including tubular rod members arranged in telescoping relation, and a detachable device rigidly securing said rod members in the telescoping relation, said device consisting of three cooperative parts, one of said parts consisting of a bar extending through a second one of said parts and having means which projects transversely through one of said rod members and impinges on the other rod member.

2. A metallic structure including rod members, and a device to rigidly secure the rod members in overlapping relation, said device consisting of a cross-bar having an abutment on one end and a longitudinal slot therein near its opposite end, said cross-bar extending through said rod members, a second abutment which extends through said slot, the second abutment having projections which extend through one of said rod members and impinging on the other rod member, and a wedge shape key which extends through said slot to cooperate with said cross-bar and the second abutment to cause said abutments to set up a clamping action to retain the device in functioning position.

3. A metallic structure of the character described including leg sections arranged in telescoping relation, and a device to rigidly secure said leg sections in the telescoping relation, said device including an abutment having a projection, and pressure exerting means which cooperates with said abutment to set up a clamping action to retain the device in functioning position with said projection extending through one of said leg sections and impinging on the other leg section for electrical conduction purposes.

4. A structure including tubular rod members arranged in telescopic relation, there being holes

10
15

5

in the outer rod member, a cross-bar extending transversely through said members, a fixed abutment on one end of said cross-bar bearing on the outer rod member, said cross-bar having a longitudinal slot therein, a separate abutment extending through said slot, projections on said abutments which extend through said holes, respectively, in the outer rod member and contact the inner rod member, and pressure exerting means extending through said slot which cooperates with said cross-bar and the separate abutment to cause the fixed abutment and projections to clampingly engage the respective rod members to rigidly secure them to each other.

5. A metallic structure including rod members arranged in telescoping relation to each other, a T-shape securing part consisting of a cross-bar and an abutment on said cross-bar, said cross-bar having a longitudinal slot therein, said cross-bar extending transversely through the over-lapping portions of said rod members and the abutment contacting the outer rod member, a second abutment disposed in said slot and having means contacting the inner rod member, and a wedge shape key disposed in said slot to exert a wedging action in conjunction with the cross-bar and second abutment to retain said means and the abutment on the T-shape part in clamping engagement with the respective rod members.

6. A structure as set forth in claim 5, wherein said means consists of pointed projections.

7. A structure including tubular rod members arranged in telescoping relation, and a detachable device rigidly securing said rod members in the telescoping relation, said device having securing means at the opposite ends thereof disposed at opposite sides of the rod members and tightly bearing toward each other against each of said rod members.
